COMBINED HAND STAMP DUPLICATOR AND COUNTER

William D. Mason, Norfolk, Jack H. Mason, Princess Anne, and Porter H. Mason, Norfolk, Va., assignors to The Multistamp Company, Norfolk, Va., a partnership

Application February 3, 1959, Serial No. 54,438

Term of patent 14 years

(Cl. D64—11)

The dominant features of the design are shown in full lines.

We claim:

The ornamental design for a combined hand stamp duplicator and counter, substantially as shown and described.
